UNITED STATES PATENT OFFICE.

JOSEPH F. BASHAM, OF EVANSVILLE, INDIANA, ASSIGNOR, BY MESNE ASSIGNMENTS, TO EVANSVILLE TOOL WORKS, INCORPORATED, OF EVANSVILLE, INDIANA, A CORPORATION OF INDIANA.

WEDGE FOR TOOL HANDLES.

Application filed January 8, 1923. Serial No. 611,238.

To all whom it may concern:

Be it known that I, JOSEPH F. BASHAM, a citizen of the United States, residing at Evansville, Vanderburgh County, Indiana, 5 have invented certain new and useful Improvements Relating to Wedges for Tool Handles, of which the following is a specification.

Tools such as hammers, hatchets, axes, 10 adzes, etc., have been held upon their handles respectively by means of wedges adapted to expand the wood of the handle into tight contact with the tool head at the eye. The present invention has for 15 its principal object the provision of a simple and cheap form of wedge which will not only give the desired expansion to the wood but which will automatically lock itself therein, and which form of wedge has 20 the advantage of being susceptible of further inward driving from time to time to restore the desired tight connection as the wood dries out.

The present improvements contemplate a 25 wedge having the inner end portion thereof formed with relatively high and relatively low areas on lines or ridges which are on lines in general diagonal to the longitudinal direction of the wedge. In a 30 preferred construction such inner end portion is ogee, or with a compound twist therein, the sharp end of the wedge defining what is sometimes known as a line of grace. It is old in the art to provide wedges 35 which are ogee, or having a compound bend, but heretofore such shape has extended throughout the wedge body from end to end. The present invention distinguishes from the prior art in this respect in that only 40 one end portion of the improved wedge has the substantially ogee shape, in a specific construction, and, broadly in having the diagonal recess construction constituting a lock for the wedge.

45 In the accompanying drawings, which form a part of this specification, Figure 1 is a side view of the preferred form of my improved wedge; Fig. 2 is a view of the outer end thereof; Fig. 3 is a view toward the inner end thereof; Fig. 4 is a 50 fragmentary view of a hammer partly in section showing the application of the wedge; Fig. 5 is a sectional view as on the line 5—5 of Fig. 4; Fig. 6 is a sectional

view as on the line 6—6 of Fig. 4; Fig. 7 55 is a sectional view as on the line 7—7 of Fig. 4; Fig. 8 is a view showing the end of the hammer of Fig. 4; Fig. 9 is a perspective view of a simple form of wedge construction old in the art; Fig. 10 is a 60 side view and Fig. 11 is an end view of a modified form of wedge; Figs. 12 and 13 shown in side and end view respectively another modification; and Fig. 14 is a fragmentary end view showing how several 65 smaller wedges may be employed.

In making my improved wedge of Fig. 1 we may assume first a wedge of ordinary construction such as shown in Fig. 9 made of iron. If we will next assume that the inner or substantially sharp end of the wedge be formed ogee, substantially as shown in Fig. 3, my improved form of wedge would be produced. In actual practice the wedge would ordinarily be forged 75 between dies.

The maximum departure of my improved wedge 10 from the ordinary wedge shown in Fig. 9 occurs at the inner or sharp edge, where the ogee or other special shape 80 is most pronounced. The twist or slanting construction is less pronounced toward the outer end of the wedge as will be noted from a comparison of Figs. 6 and 3. At about the line 11 of Fig. 1, the twist or 85 special formation substantially fades out, and from the line 11 to the outer end of the wedge, the wedge has substantially flat sides, these sides diverging toward the outer end 90 typically wedge fashion. From the line 11 to the inner or sharp edge of the wedge the thickness of the metal is gradually reduced, so that from the outer end to the inner end of the wedge any vertical cross-section would show a wedge-shaped structure. 95

In applying my new wedge it is simply set upon the end of the handle at the eye as shown in Fig. 8 and forced home, as by hammer blows. The result of the tapering 100 construction is to force the wood into contact with the eye of the tool head throughout the extent of the wedge. The effect of the ogee cutting edge is to define an ogee line of cleavage through the wood to the extent that the wedge is driven inward. If the wedge were ogee throughout its body, as in the prior art, this ogee line defined by

the cutting edge would be preserved from end to end of the wedge and there would be nothing but frictional contact to maintain the wedge in place. It has been clearly demonstrated that such frictional contact alone is not sufficient to hold such handle-holding wedges in position under conditions of use. According to these improvements, however, the ogee path defined by the cutting edge is destroyed in large part by the following-after portions of the wedge, and more and more so as the wedge is driven home, except, of course, for the path of cleavage at or close to the sharp end. The flat sides diverging outward from the line 11 of Fig. 1 and the diverging walls of the wedge merging into the flat sides there force the wood to take on other lines and shapes where it contacts the wedge with the result that the wood is strongly crowded into contact with the wedge at all points on the sides thereof, and since the construction given to the inner portion of the wedge produces relatively elevated and relatively depressed or concavo-convex portions which are on lines diagonal with respect to the length of the wedge and its direction of movement into the wood the wedge becomes locked in the wood and form diagonally disposed recesses in opposite sides of the wedge, through compression of the wood in these diagonal pockets or recesses. If the wedge were free to be retracted with a twisting or turning motion it would come away as readily as ordinary frictional contact would permit, but since the outer portion of the wedge firmly holds it against the possibility of twisting motion, the wedge would have to displace tightly bound wood fibers, as distinguished from merely frictionally sliding away from them, before it could come out.

According to the modification of Figs. 10 and 11 the free edge portion of the wedge 15 is given several diagonally-arranged bends or elevations 16 with intervening relatively low channels or areas 17, the channels and ridges merging into the flat surfaces respectively on opposite sides of the outer end portion of the wedge. According to Figs. 12 and 13 the free end portion of the wedge 20 is formed with a single

diagonal depression 21 on one side and a rib-like elevation 22 on the other.

At any time that the handle dries out and the head becomes loose thereon the wedge 10, 15 or 20 may simply be driven in farther to restore the fit, and with a renewed locking hold thereof upon the wood.

Reference should be had to the appended claims to determine the scope of the improvements herein set forth.

I claim:

1. A handle-holding wedge of the character described comprising a wedge body substantially rectangular in side view, relatively thick at its normally outer end, and substantially thin and sharp at its normally inner end, inner portions of the body having two concavo-convex formations spaced apart, oppositely directed in end view and diagonally directed in side view and merging into each other on substantially ogee lines in end view, said formations providing on each side of the wedge a trough-like recess diagonally directed, substantially half the width of the wedge at its sharp edge and gradually decreasing in width and depth toward the thick end of the wedge, the relatively thick outer portions of the wedge being free of said concavo-convex formations.

2. A handle-holding wedge of the character described comprising a wedge body substantially rectangular in side view, relatively thick at its normally outer end and substantially thin and sharp at its normally inner end, the inner sharp edge defining a continuous line extending from one inner corner to the other inner corner and having a plurality of lateral departures from a straight line, inner portions of the wedge body being formed substantially concavo-convex at a plurality of places forming trough-like recesses terminating in the sharp edge and extending normally outwardly and in diagonal directions in side view, the arrangement of parts being such that when the wedge is normally driven into the handle a single line of cleavage of the wood occurs and fibers of the wood are compressed in said recesses.

JOSEPH F. BASHAM.
